HEAD BAND ATTACHMENT FOR RESPIRATORS

Harry F. Shindel, Reading, and Allen D. Brandt, Wyomissing, Pa., assignors to Willson Products, Inc., Reading, Pa., a corporation of Pennsylvania

Application June 4, 1935, Serial No. 24,834

5 Claims. (Cl. 128—141)

This invention relates to respirators employing a head band or the like to secure them in position on the face of a wearer, the main objects being to guard against leakage of impure air through such band connection and to provide an improved connection insuring a positive support, more accurate fit, and greater comfort in wearing the same.

The mask portion of the respirator is preferably made of flexible material, as rubber, or the like, molded to conformingly fit the face, usually the mouth and nose only, and the head band attachment has heretofore commonly been provided by headed studs inserted through suitable apertures formed in the molded wall. This type of head band connection has proven satisfactory when slight leakage was not dangerous and the mask material was comparatively firm. Modern practice calls for a softer mask of increased flexibility to more readily conform to the curvatures of the face and tightly fit against the same without uncomfortable pressure at any point. In this softer mask, strain of the head band on the headed studs tends to tilt and strain them in their wall apertures, stretching the latter to cause a dangerous source of leakage for certain uses, and distorting the mask more or less in tauting the band to press the mask against the face.

The present improvements are intended to overcome the aforesaid difficulties and to provide a mask connection which can in no manner cause leakage and that will insure a better support for the mask and freedom from distortion of the latter due to strain of the head band.

With the above objects in view the invention comprises the head band attaching device more fully described in connection with the accompanying drawing, and the novel features of which are specifically set forth in the appended claims.

Fig. 1 indicates in side elevation a respirator mask having band attaching ears embodying the present invention.

Fig. 2 is a cross sectional view on the line 2—2 of Fig. 1, showing the attaching ears formed as part of the rim of an attachment securing clamping cap.

Fig. 3 is a cross sectional view, similar to Fig. 2, but indicating the attaching ears as part of a ring engaged by the clamping cap.

Fig. 4 is a perspective view of a bent-wire modification of the band attaching ring shown in Fig. 3.

Figs. 5 and 6 are respectively a transverse section and front elevation of the embodiment shown in Fig. 2.

Figs. 7 and 8 are correspondingly sectional and elevated views of the embodiment shown in Fig. 3.

The respirator shown in the drawing is well known and comprises a face-conforming mask 5 which is of continuous character and adapted to fit over the nose and mouth of a wearer and tightly fit against the face of the latter to exclude admission of outside air during inhaling, except as admitted through its air-inlet aperture 6, shown formed with a usual surrounding attaching flange 7. This mask is preferably molded of comparatively soft rubber or other flexible material impervious to fluids, and carries, for protection against admission of impure air, a filtering cartridge or air-supply tube not shown and attached to the mask, as by the well-known end-apertured clamping screw cap 8, having a rim portion 9 adapted to engage the flange 7 of the mask as shown.

Preferably, the mask 5 is tubular in construction and may be relatively elongated to permit essential clearance between the face of the wearer and the more rigid elements usually connected to the clamping cap 8. The opposite edges thereof are formed differently, the forward edge comprising the clamping flange 7 and the rearward edge having the face conforming configuration shown in the drawing.

As stated before, the present improvements relate to a head band connection for a respirator as above set forth, and essentially comprises band-attaching ears 10, 10 adapted to lie closely adjacent against opposite outer side walls of the mask 5, and means for supporting said ears behind the mask attaching flange 7, so that strains of the head band are distributed around the air-inlet aperture 6 in drawing the mask against the face of a wearer.

The support for the ears 10, 10, may vary as later herein described, with the object in view of distributing strains around the inlet 6 by a support bearing against the outer surface of the imperforate rubber mask free of any possible piercing of the latter to cause leaks for unconditioned air.

As shown in Figs. 1 and 2, and detail views 5 and 6, the ears 10, 10 are formed as integral portions of the clamping cap 8, and may be readily made in cutting the end apertures of the cap 8 to leave the rim portion with extension to be bent up as shown to form said ears 10, 10. When the cap rim is engaged over the mask flange 7, and seated against the inner face of the latter by clamping engagement with an air conditioner 55

attachment, as filter 11, the ears 10, 10 will extend rearward and lie against the sides of the mask, and any attaching means, as studs 12, may be provided to secure the head band attaching 5 end 13.

Figs. 3, 7, and 8 show ears 10', 10' formed as part of a supporting ring 15, extending rearwardly from the inner edge of its aperture. This ring 15 is adapted to engage over the mask flange 7' 10 and to be clamped between the inner face of the latter and the rim 9' of a clamping cap 8' as shown.

With the head band attaching device above described, the mask wall is free from any aperture likely to cause leakage, and the spaced ears are properly positioned and supported so that the strains of the tauted head band strap are spread around the mask inlet aperture to more 20 equally distribute the pressure of the inner edge of the mask against the wearer's face, with freedom to flex as required, and avoidance of distortion more or less inherent in the connections heretofore known.

The supports so far described are shown as 25 made of flat metal or other suitable flat material, but it is obvious that they may, if desired, be made of bent wire, as seen in Fig. 9, indicating a collar ring 18 with loop ears 19, 19, spaced from the ring by wire twists 20, 20 to prevent 30 opening of the ring or loop ears when strained by pull on the head band.

It is also obvious that the ear supporting rings may be made in two parts relatively adjustable to properly position the ears in varying position 35 if required.

It is intended to include the above shown and suggested modifications as well as others, not specifically mentioned, that are within the spirit of the invention as defined in the following claims.

40 We claim:

1. In a respirator the combination with a face mask of flexible material having an air inlet provided with a surrounding flange, of a flanged

mask extension and head-band attaching means jointly secured to the mask by clamping engagement of the flanges.

2. In a respirator the combination with a face mask of flexible material having an air inlet 5 provided with a surrounding flange, of a flanged mask extension and head-band attaching means jointly secured to the mask by clamping engagement of the flanges, said band attaching means comprising rigid band engaging ears overlying 10 the adjacent flexible body of the mask.

3. In a respirator the combination with a face mask of flexible material having an air inlet 15 provided with a surrounding flange, of a flanged mask extension secured to the mask by clamping engagement of the flanges, and a separately formed mask-encircling ring engaged between the clamping flanges and having band-engaging ears arranged to overlie the adjacent flexible body of the mask.

4. In a respirator the combination with a flexible mask having an air inlet with a surrounding external flange, and an air-conditioner inlet attachment having a clamping rim engageable with said mask flange, of a head band attachment comprising band attaching ears adapted to overlie the mask body and a mask encircling rim adapted to be clampingly engaged between said mask flange and clamping rim.

5. In a respirator the combination with a face-conforming mask of molded flexible material having an inlet opening formed with a surrounding exterior flange, and an inlet-attachment having a rim adapted to clampingly engage said mask flange, of a head-band attaching device comprising a flat-ring adapted to be interposed between said rim and mask flange, and a pair of spaced band-attaching ears formed integrally with said ring and bent upwardly therefrom to overlie the outer wall of the mask on opposite 40 sides of the latter.

HARRY F. SHINDEL.
